UNITED STATES PATENT OFFICE.

WILLIAM R. MENGEI, OF CHICAGO, ILLINOIS.

STEREOPTICON.

1,342,561.

Specification of Letters Patent.

Patented June 8, 1920.

Application filed March 29, 1918, Serial No. 225,418. Renewed November 13, 1919. Serial No. 337,867.

To all whom it may concern:

Be it known that I, WILLIAM R. MENGEI, a citizen of the United States, residing at Chicago, in the county of Cook and State 5 of Illinois, have invented a certain new and useful Improvement in Stereopticons, of which the following is the specification.

This invention relates to that class of portable stereopticons in which the main 10 inclosing casing is of the suit-case form, and in which the series of views or pictures are on a transparent band or strip, and the present improvement has for its object:—

To provide a simple and efficient structural formation and association of parts, whereby the heat from the incandescent lamp used as the source of illumination of the apparatus, is effectively intercepted and carried away before reaching the inflammable film upon which the series of views or pictures are printed, all as will hereinafter more fully appear.

In the accompanying drawings:—

Fig. 1, is a side elevation illustrating 25 the general association of parts in the present invention, the inclosing casing being shown in section and having the form of an ordinary suit case.

Fig. 2, is a top view of the film feeding 30 mechanism shown to the right in Fig. 1.

Fig. 3, is a central longitudinal section of the same.

Fig. 4, is a horizontal section of the same on line $x-x$, Fig. 3.

Fig. 5, is a fragmentary end elevation of the film feeding mechanism.

Fig. 6, is an elevation of the inner face of the apertured film guiding plate.

Fig. 7, is a detail elevation of the outer 40 face of the same.

Fig. 8, is an enlarged detail longitudinal section of the film feeding mechanism.

Fig. 9, is a longitudinal sectional elevation of said film feeding mechanism.

Like reference numerals indicate like 45 parts in the several views.

Referring to the drawings, 20 designates the main inclosing casing of a rectangular box or suit case form, as usual in the present 50 type of stereopticons.

21 designates the lamp house of the usual rectangular form, arranged at one end of the inclosing casing 20 and inclosing the usual incandescent electric lamp 22, the socket 23 of which is preferably connected by a flexible conductor 24 with a socket plug 25 in the adjacent end wall of the main casing 20.

26 designates a bracket frame attached to the lamp socket 23 and secured in a vertically adjustable manner to an upright post 60 or standard 27 by a set screw 28, thus providing a vertical adjustment for the incandescent electric lamp 22. The post or standard 27 is provided with a supporting base 29 adapted for longitudinal adjustment 65 on the floor of the main casing 20 by means of a bolt 30 and wing nut 31 for the purpose of effecting an adjustment of the lamp 22 along the light center of the apparatus.

32 and 33 designate the pair of lenses constituting the condenser of the apparatus, and which in the present improvement are mounted in the front and rear walls of a rectangular shell or casing 34, arranged immediately in front of the lamp house 21 and 75 removably supported in place by transverse guides 36 and 37 upon the respective top and bottom walls of the main casing 20 as shown.

35 designates a plurality of perforations 80 in the side walls of the aforesaid shell or casing 34, adapted to permit of a very effective circulation of air through the interior of said shell or casing to intercept and carry off the heat rays in their passage between 85 the pair of lenses 32, 33 aforesaid.

38 designates the frame or housing of the film carrying and actuating mechanism of the apparatus, arranged at the other end of the main casing 20 in line with the lamp 90 house 21, and provided with the usual objective 39.

40 and 41 designate the upper and lower film spools or reels journaled on the frame or housing 38 and having operative connections with the film actuating mechanism in 95 manner hereinafter described.

43 designates the usual film guiding plate carried by the frame or housing 38, and formed with the usual light aperture 42, 100 and with a shallow vertical recess 44 for the reception and guidance of the picture film in its movement past the light aperture 42 aforesaid.

51 designates a carrying head or block 105 upon which the hereinafter described film feeding member 49 is mounted. Said carrying head or block is slidably mounted on vertical guide rods 52, fixedly arranged in bracket lugs 53 and 54 on the inner face of 110 the film guiding plate 43 aforesaid, and the amount of movement of the carrying head 51 is regulated by an adjustment screw 55 mounted in the lower lug 53 aforesaid.

- The film feeding member 49 above referred to, is of a block form, pivoted by a pivot pin 50 on the carrying head 51 aforesaid, and having at one end teeth or detents 48 adapted to project through vertical slots 47 formed in the film guiding plate 43 and operatively engage in the usual side perforations of the picture film.

56 designates a coil spring associated with the film feeding member 49 and tending to normally hold the teeth or detents 48 in a projected position.

57 designates a toe or extension on the film feeding member 49, adapted to engage the under surface of the upper lug 54, so as to move the teeth or detents 48 out of the projected position above described, when said member 49 is in its raised position, as shown in Fig. 8.

20 58 designates a spring the lower end of which has bearing on the frame or housing 38 aforesaid, while the upper end of said spring is secured by means of a pin 59 to a lateral extension 60 of the carrying head 51 aforesaid, the arrangement is such that the tension of the spring 58 will normally hold the carrying head 51 at the upward portion of its movement.

61 designates a vertically arranged operating rod or stem, the upper end of which extends through the top wall of the main casing 20 and is provided with an operating knob or handle 62, while its lower portion is guided in guide lugs on the inner face of the film guiding plate 43 and has operative engagement with the carrying head 51, as shown in Fig. 6, to impart positive downward movement to the same.

63 designates a connecting rod or link extending from the carrying head 51 to a rock lever 64 arranged to oscillate loosely on the carrying shaft of the lower or take-up film spool or reel 41 aforesaid, and carrying a ratchet pawl or dog adapted to engage a ratchet wheel 65 fixed on said carrying shaft, so that with a downward movement of the carrying head 51 to effect a movement of the picture film past the light aperture 42 of the apparatus, a partial rotation of the film reel 41 will be simultaneously effected to take up the film as it is intermittently fed through the mechanism.

66 designates the hinged gate by which the picture film is confined to the vertical guiding recess 44 of the film guiding plate 43, and will be formed with the usual light passage in line with the light aperture 42 of the associated film guiding plate 43.

67 designates a vertical plate or partition formed with a light opening 68 in line with the light apertures of the film guiding plate 43 and film confining gate 66, and in the present improvement said opening 68 is provided with a transparent plate 69 of glass

or the like. Said plate or partition 67 is secured in spaced relation to the rear face of the film confining gate 66 by horizontal studs or pins as shown in Fig. 3, to provide an open space between the parts adapted to provide a ventilating passage for the air and aid in intercepting and carrying away the heat rays passing along the light path of the apparatus.

70 designates a spring tending to hold the film confining gate 66 in its normally closed position.

72 designates lateral lugs on the base of the frame or housing 38 aforesaid, adapted to receive fastening screws 71 by which said frame or housing is secured to the floor of the main casing 20.

Having thus fully described my invention, what I claim as new and desire to secure by Letters Patent, is:—

  1. In a stereopticon, the combination of a main casing, a lamp house arranged at one end of said casing, a film feeding mechanism arranged at the other end of said casing, a rectangular shell arranged in said casing intermediate the lamp house and film feeding mechanism aforesaid and provided with a plurality of perforations in its vertical side walls, and condenser lenses mounted in the front and rear walls of said shell, substantially as set forth.
  2. In a stereopticon, the combination of a main casing, a lamp house arranged at one end of said casing, a film feeding mechanism arranged at the other end of said casing, a rectangular shell arranged in said casing intermediate the lamp house and film feeding mechanism aforesaid and provided with a plurality of perforations in its vertical side walls, condenser lenses mounted in the front and rear walls of said shell, a film confining gate associated with the film feeding mechanism aforesaid, and a vertical partition secured in spaced relation to said gate, substantially as set forth.
  3. In a stereopticon, the combination of a main casing, a lamp house arranged at one end of said casing, a film feeding mechanism arranged at the other end of said casing, a rectangular shell arranged in said casing intermediate the lamp house and film feeding mechanism aforesaid and provided with a plurality of perforations in its vertical side walls, condenser lenses mounted in the front and rear walls of said shell, a film confining gate associated with the film feeding mechanism aforesaid, and a vertical partition secured in spaced relation to said gate and provided with a light opening having a transparent closure, substantially as set forth.

In testimony whereof, I have signed the foregoing specification.

WILLIAM R. MENGEL.
